UNITED STATES PATENT OFFICE

JOHN W. COSGROVE, DECEASED, LATE OF MEDFORD, MASSACHUSETTS, BY CAROLINE E. COSGROVE, ADMINISTRATRIX, OF MEDFORD, MASSACHUSETTS, ASSIGNOR TO UNITED SHOE MACHINERY CORPORATION, OF PATERSON, NEW JERSEY, A CORPORATION OF NEW JERSEY

CEMENTING MACHINE

Application filed June 14, 1929. Serial No. 371,001.

This invention relates to cementing machines and is herein illustrated in a cementing machine having a work supporting device positioned below a cement applying device.

It is common in many types of cementing machines, and especially in machines used for cementing shoe parts, to apply the cement by means of a driven roll positioned over the work and to hold the work in contact with the cement applying roll by means of a work supporting roll positioned below the work and directly underneath the cement applying roll. In such machines difficulty is sometimes experienced, especially when light cements of a considerable degree of fluidity are employed, because the cement is apt to drip from the cement applying roll and, being caught by the work supporting roll, to be accidentally applied to the work, smooching the same. This detrimental result is frequently the result of carelessness upon the part of the operative who leaves the machine running without shutting off the supply of cement so that, even though the machine operates perfectly without dripping when pieces of work are being passed through the machine at frequent intervals, the machine may not be able to take care of the cement upon the applying roll when left running for a substantial period of time without the presentation of a piece of work.

An object of the invention, accordingly, is to provide an improved cementing machine having a displaceable guard for protecting the work of the machine.

As herein illustrated and in accordance with features of the invention, the guard comprises a fixed annular portion surrounding a large fraction of the under side of a work supporting roll and a movable portion mounted on a pivot arm and adapted to be interposed between the applying and supporting rolls to supplement the fixed portion of the guard so as to catch any cement which drips from the cement applying device.

In the drawings,

Fig. 1 is an angular view of the work engaging parts of a cementing machine showing the novel guard in effective position,

Fig. 2 is an end view of the same, Fig. 3 is an end view on a smaller scale with the guard dropped to inoperative position, showing a piece of work passing through the machine, and

Fig. 4 is a plan view of the guard support, showing its connection to the work supporting roll.

Although it will be evident that the novel guard can be applied to various types of machines, it is herein illustrated as applied to a machine of the type shown in an application of John W. Cosgrove, deceased, Serial No. 259,537, filed March 6, 1928, to which reference may be had for a description of parts of the machine not herein fully shown or described. The machine comprises a displaceable guard plate 10 positioned between a driven cement applying roll 12 supported in fixed bearings in a frame member 14 and a work supporting roll 16 mounted on the end of a shaft 17 which is journaled in a movable arm 18 so that the work supporting roll may be dropped to allow the insertion of a piece of work 20 and then raised to grip the work (Fig. 3) between the cement applying roll and the work supporting roll. On this arm 18 is mounted an adjustable gage support 22 carrying an edge gage 26 adjustable thereon. Secured to the gage support 22 by a slotted arm 23 is an annular guard 30 surrounding approximately three quarters of the under side of the work supporting roll 16 but left open at the top to permit the coaction of said rolls 12 and 16 with an interposed piece of work 20. The forward end of the gage support 22 is turned inwardly and has a forked portion 25 engaging a peripheral groove in the hub of the roll 16 so that the latter may be adjusted in and out with respect to the cement applying roll 12 to vary the width of the marginal stripe of cement applied to the work. This feature is not claimed herein since it is claimed in the afore-mentioned application.

Supplementing this annular guard 30 is the displaceable guard 10 in the form of a thin plate slightly curved and supported by screws upon the upper end of a swinging arm 32. This arm 32 is pivoted at 34 at a point beneath

the work supporting roll upon the lower end of an arm 36 secured to the guard arm 23. It will be seen thus that the roll 16 as well as the guard members 10 and 20 are adjustable with the gage.

5 In the use of the machine, the displaceable guard member 10 will be kept in the position shown in Fig. 1 until the operator is ready to use the machine. It may then be moved aside by swinging the arm 32 to the position shown 10 in Fig. 3, to allow the machine to apply cement to pieces of work interposed between the cement applying device 12 and the work supporting device 16, these pieces of work being guided by the gage 26. When the operator 15 finishes one batch of work and there is to be a substantial interval before the presentation of another batch of work, the guard member 10 is swung into position shown in Figs. 1 and 2, where it will catch any drippings from 20 the cement roll 12.

Having thus described the invention what is claimed as new and desired to be secured by Letters Patent of the United States is:

25 1. In a cementing machine, a cement applying device, a work supporting device disposed below said cement applying device, means for protecting said work supporting device from cement drippings comprising a guard movable between two positions in one of which it is adapted to be interposed between said devices.

30 2. In a cementing machine, a cement applying device, a work supporting device beneath said cement applying device, an annular guard surrounding a portion of said work supporting device, and a guard supplementing said annular guard and movably mounted thereon so that it may be positioned between 35 the cement applying device and the work supporting device and moved to another position to permit said devices to coact with an interposed piece of work.

35 3. In a cementing machine, a cement roll, a work supporting roll beneath said cement roll, a movably mounted guard member adapted to be positioned between said rolls when the machine is inactive and to be moved to an out of the way position to permit said 40 rolls to coact with an interposed piece of work.

45 4. In a cementing machine, a cement roll, a work supporting roll mounted on a movable arm in a position beneath said cement roll, 50 guards secured to said arm comprising a fixed portion surrounding the lower portion of the work supporting roll, and a movable portion adapted to be interposed between the rolls to protect that portion of the work supporting 55 roll which is not protected by the fixed portion of the guard, said movably mounted portion being adapted to be displaced to permit said rolls to coact with an interposed piece of work.

60 5. In a cementing machine, a cement roll,

a work supporting roll mounted in a movable arm and positioned below said cement roll, a gage support secured to said bracket, and a guard supported upon said gage support comprising a movably mounted portion adapted to be interposed between the rolls or to be displaced to allow said rolls to coact with an interposed piece of work.

65 In a cementing machine, a cement roll, a work supporting roll journaled in a pivoted arm and positioned below said cement roll, a gage support secured to said arm, a guard carried by said gage support and comprising an annular portion surrounding the lower portion of the work supporting roll, and another portion adapted to be interposed between said 70 rolls, said latter portion being mounted upon an arm pivoted at a point below said work supporting roll.

In testimony whereof I have signed my name to this specification.

CAROLINE E. COSGROVE,
*Administratrix of the Estate of John W.
Cosgrove, Deceased.*
